JUG

Floyd E. Pettengill, Millville, N.J., assignor to Armstrong Cork Company, Lancaster, Pa., a corporation of Pennsylvania

Filed Sept. 29, 1960, Ser. No. 62,304

Term of patent 14 years

(Cl. D58—25)

Fig. 1 is a perspective view of a jug showing my new design;

Fig. 2 is a perspective view thereof turned 90° clockwise from the position shown in Fig. 1;

Fig. 3 is a top plan view of the jug; and

The dominant features of my design reside in the portions shown in full lines.

This application is a continuation-in-part of my co-pending application, Serial No. D. 58,935, filed January 5, 1960, now abandoned.

I claim:

The ornamental design for a jug, substantially as shown and described.
